UNITED STATES PATENT OFFICE.

STACY B. HASELTINE, OF CHICAGO, ILLINOIS, ASSIGNOR TO WILLIAM H. MINER, OF CHAZY, NEW YORK.

DRAW-BAR AND YOKE CONNECTION.

1,286,613.

Specification of Letters Patent.

Patented Dec. 3, 1918.

Application filed April 27, 1918, Serial No. 231,062.

To all whom it may concern:

Be it known that I, STACY B. HASELTINE, a citizen of the United States, residing at Chicago, in the county of Cook and State of Illinois, have invented a certain new and useful Improvement in Draw-Bar and Yoke Connections, of which the following is a full, clear, concise, and exact description, reference being had to the accompanying 10 drawings, forming a part of this specification.

This invention relates to improvements in draw bar and yoke connections.

One object of the invention is to provide a 15 detachable draw bar and yoke connection for railway draft riggings and wherein may be employed the standard draw bars and old yoke straps without modification of the latter.

20 Another and more specific object of the invention is to provide a detachable draw bar and yoke connection wherein are utilized the standardly located rivet receiving holes of the draw bar and yoke, detachable pins penetrating said rivet holes, a band-like structure for retaining said pins in position, and a simple expedient for preventing displacement of said band-like member when all the parts are assembled.

25 In the drawing forming a part of this specification,

Figure 1 is a side elevational view of a portion of a standard draw bar and yoke strap showing my improvements in construction therewith.

30 Fig. 2 is a top plan view of the structure illustrated in Fig. 1, parts of the yoke being broken away. Fig. 3 is a vertical, sectional view, taken substantially on the line 3-3 40 of Fig. 1. And Fig. 4 is a detail perspective of one of the retaining plates for the band.

In said drawing, 10 denotes a standard draw bar having the usual upper and lower 45 shoulders 11-11 and standardly located rivet receiving holes 12-12 in the upper and lower walls thereof. A wrought iron U-shaped yoke of well known design is indicated at 13, the same having the free ends 50 of the arms thereof also provided with standardly located rivet receiving holes 14-14. The ends of said yoke arms are also shown as provided with inturned gibs 15-15 as sometimes employed.

55 In order to detachably connect the draw

bar and yoke without modification of either, I employ the following arrangement: Two upper steel, relatively short pins 16-16 are extended through the upper sets of rivet holes in the yoke and draw bar and a corresponding pair of pins 116 are extended through the lower sets of rivet holes in the yoke and draw bar. All of said pins 16 and 116 are provided with heads 17 so as to prevent the pins from passing completely 60 through the rivet holes and said heads 17 are left projecting beyond the adjacent surfaces of the yoke strap for reasons appearing hereinafter. To hold the pins in place; I employ a band-like arrangement consist- 65 ing of an inverted U-shaped plate or stirrup 18 which extends over the upper pin 16 and down the sides of the draw bar, and a removable cross key 19 at the bottom forming the fourth side of the band. Said key 19 70 may be held against accidental displacement by any suitable means, such as the cotter 20 and shouldered end 21. Preferably, I employ a U-shaped plate 22 fitting over the key 19 within the band although the same 75 is not necessary.

It is obvious that the arrangement above described will hold the pins 16-116 in place provided the band does not slip lengthwise of the yoke. In order to prevent this longitudinal displacement and do so at a minimum expense, I utilize two plates 23 and 24. The upper plate 23 is interposed between the top portion of the band and the upper yoke arm, said plate being suitably apertured, as 80 indicated at 25, to accommodate the heads of the pins 16, said plate 23 being of a thickness corresponding to the thickness of the said heads. It is thus obvious that the plate 23 cannot shift lengthwise because of its 85 shouldered engagement with the headed pins 16. In order to prevent the band or upper portion thereof from shifting, the ends of said plate 23 are upturned or shouldered, as indicated at 26, so as to engage the front and 90 rear edges of the top section of the band. The lower plate 24 is similarly apertured to accommodate the heads of the lower pins 116, as indicated at 27, and to prevent shifting of the lower portion of the bar, said plate 24 95 is provided with laterally extended shoulders 28-28 at the four corners thereof, said shoulder overlapping the side edges of the depending arms of the stirrup 18.

With the arrangement described and illus- 100

trated, it is evident that I am enabled to provide a detachable connection for the usual rivet type of yoke and without modification of the latter, thereby effecting a large saving to the railroads by permitting the re-employment of the old yoke straps. Furthermore, the band for retaining the pins may be cheaply manufactured either in the form of cast steel, wrought iron, or steel plate and by the use of the inexpensive plates 23 and 24, or either of them, I positively prevent accidental displacement of the band.

I claim:

1. A detachable connection for draw bars and yokes having alined perforations for the reception of fastening means such as rivets, said connection comprising headed elements adapted to be inserted into said perforations with the heads projecting beyond the outer sides of the yoke arms, a band-like member arranged to extend around the draw bar, yoke, and said elements to hold the latter in place, and means having shouldered engagement with said band-like member and said projecting heads, adapted to prevent longitudinal displacement of said band-like member relatively to the yoke when all the parts are in assembled relation.
2. A detachable connection for draw bars and yokes having alined perforations for the reception of fastening means such as rivets, said connection comprising headed elements adapted to be inserted into said perforations with the heads projecting beyond the outer sides of the yoke arms, a band-like member arranged to extend around the draw bar, yoke, and said elements to hold the latter in place, and means, having shouldered engagement with said band-like member and said projecting heads, adapted to prevent longitudinal displacement of said band-like member relatively to the yoke when all the parts are in assembled relation, said band-like member including a U-shaped stirrup forming three sides of the band and a detachable key extending between the free ends of said stirrup and forming the fourth side thereof.
3. A detachable connection for draw bars

and yokes having alined perforations for the reception of fastening means such as rivets, said connection comprising headed elements adapted to be inserted into said perforations with the heads projecting beyond the outer sides of the yoke arms, a band-like member arranged to extend around the draw bar, yoke, and said elements to hold the latter in place, and means, having shouldered engagement with said band-like member and said projecting heads, adapted to prevent longitudinal displacement of said band-like member relatively to the yoke when all the parts are in assembled relation, said means including a plate arranged to be interposed between one wall of the band-like member and the adjacent arm of the yoke, the plate being apertured to accommodate the heads of said elements and shouldered at its ends to engage the band-like member.

4. A detachable connection for draw bars and yokes having alined perforations adapted for the reception of fastening means such as rivets, said connection comprising a plurality of headed pins adapted to penetrate said alined perforations, a band arranged to surround said pins, draw bar and yoke when all the parts are assembled, and a plate cut away to accommodate the headed pins and having shouldered engagement with the band.

5. The combination with a draw bar and U-shaped yoke having alined standardly spaced rivet receiving holes, of upper and lower sets of relatively short headed pins penetrating the upper and lower sets of said holes, the heads of said pins projecting beyond the adjacent surfaces of the yoke arms, a plate fitting over the heads of two of said pins, a band surrounding the draw bar, yoke and all of said pins, said plate having shoulders formed at its ends overlapping the adjacent portions of said band to thereby prevent longitudinal displacement of the band.

In witness that I claim the foregoing I have hereunto subscribed my name this 13th day of April, 1918.

STACY B. HASELTINE.
